VACUUM PICK-UP FOR WAFERS

Bruce K. Miller, Mesa, and T. John Trayes, Phoenix,
Ariz., assignors to Motorola, Inc., Chicago, Ill.

Filed Mar. 28, 1974, Ser. No. 455,849

Term of patent 14 years

Int. Cl. D8—05

U.S. Cl. D8—71

FIG. 1 is a perspective view of a vacuum pick-up for wafers showing our new design.

FIG. 2 is a top view thereof.

FIG. 3 is a front view thereof.

The side opposite that shown in FIG. 1 is substantially a mirror image thereof.

We claim:

The ornamental design for a vacuum pick-up for wafers, as shown and described.
